UNITED STATES PATENT OFFICE.

JOSEPH B. WELDAY, OF DENNISON, OHIO.

SIGNALING DEVICE.

Application filed December 17, 1924. Serial No. 756,566.

This invention relates to improvements in signaling devices and more particularly to a signaling device for use by section men on railroads. Where it is necessary to make repairs on a railroad, the track foreman in charge of the work sends one of the section men along the track to a point remote from the point where the repairs are being made, with a red flag, to signal and stop any on-coming trains. As a rule, the section men are illiterate foreigners and it very often happens that the engineer or conductor of a train stopped by one of the men is unable to obtain from him any information as to the reason for stopping the train. Therefore, the present invention has as its primary object to provide a signaling device by the employment of which this difficulty may be overcome and information afforded the engineer or conductor as to the nature of the trouble, notwithstanding the inability of the section man to speak the English language or impart the necessary information.

Another object of the invention is to provide a signaling device for the purpose above stated embodying a number of signal arms or blades arranged in pairs and the blades of each pair bearing words denoting one or another of the more common causes of delay of a train, all of the blades being normally housed so as to be concealed from view and the blades being adapted to be selectively displayed by a very simple adjustment of the device, so that the track foreman may prepare the device before it is handed to the section man, to be subsequently adjusted and displayed by him, and in such manner as to preclude any likelihood of the section man making any mistake in the adjustment of the device to display the signal or warning.

The device embodying the invention is not intended to serve as a substitute for the red flag ordinarily employed by section men in signaling the engineer of a train to warn him of obstruction along the track, but as an auxiliary signaling device, the red flag being employed as has heretofore been customary to first stop the train and the signaling device being subsequently employed to apprise the engineer or conductor as to the reason for the delay, and, therefore, the present invention contemplates so constructing the device that a member thereof will con-

stitute a housing or holder for the red signal flag when the flag is not in use, thereby 55 protecting the flag from becoming soiled and likewise tending to prevent its loss.

Another object of the invention is to so construct the device that an outward and downward swinging of one of the blades of 60 any of the pairs of signal blades will, by a most simple arrangement of elements, result in a corresponding and simultaneous movement of the other blade of the pair, the blades being, as previously stated, normally 65 housed and concealed so that the device is of a compact nature when not in use and may be readily and quickly adjusted for use.

In the accompanying drawings:

Figure 1 is a perspective view of the signaling device embodying the invention. 70

Figure 2 is a vertical transverse sectional view through the device, illustrating the signal blades in full lines in normal position and in dotted lines in position to display the 75 signal borne by them.

Figure 3 is a vertical sectional view taken substantially on the line 3-3 of Figure 2, looking in the direction indicated by the 80 arrows.

Figure 4 is a fragmentary perspective view of a portion of the signaling device.

Figure 5 is a similar view of a portion of one of the signal blades.

The device embodying the invention consists of a frame structure indicated in general by the numeral 1 and comprising two side members indicated in general by the numeral 2. Each of the side members is preferably formed from a single length of sheet 85 metal bent along spaced parallel transverse lines intermediate its ends to provide spaced outer and inner plates indicated respectively by the numerals 3 and 4, and a connecting bottom portion 5, the upper ends of the 90 plates being bent toward each other at right angles and overlapped as indicated by the numeral 6. The frame structure further includes a top member 7 and a bottom member 8, and the top member is in the nature 100 of a plate secured by bolts or other suitable fastening elements 9 to the upper end portions 6 of the side members of the frame structure and having its opposite edges turned downwardly as at 10, to engage the 105 outer faces of the plates 3 of the side mem-

bers. The bottom member 8 is likewise in the nature of a metallic plate secured by bolts or other suitable fastening elements 11 to the connecting bottom portions 5 of the side members of the frame structure, and the opposite edge portions of this plate are turned upwardly at right angles as at 12, to engage the outer faces of the said plates 3 of the side members. In this manner, two spaced open-sided housing frames are provided, and extending between the plates 4 of the side members of the frame structure and upwardly through an opening 12 formed in the bottom plate 8, is a tubular stock 13, the projecting lower end of which constitutes a handle indicated by the numeral 14, whereby the device may be conveniently held and displayed. A pin 15 is secured diametrically through the upper end of the tubular stock 13 and through an eye 16 formed at the lower end of the shank 17 of a hook 18, the said shank of the hook having a head or nut 19 thereon engaging the upper side of the top plate 7 and the hook constituting means whereby the device may be suspended from the tool rack of a hand car. The upper end of the tubular stock 13 abuts squarely against the under side of the top plate 7 and it will, therefore, be evident that the stock is rigid with respect to the frame structure. The stock serves likewise as a housing for the usual signal flag indicated by the numeral 20, the lower end of the stock being adapted to be closed by a removable cap member 21 so as to retain the flag within the stock when not in use, it being understood that by merely removing the cap member 21, the flag may be instantly withdrawn and employed by the section man in signaling.

The signal displaying devices of the invention are in the nature of a plurality of pairs of signal blades, the blades of each pair being indicated in general by the numeral 22. Each signal displaying blade 22 comprises a plate 23 of oblong rectangular form provided at its lower end with an extension indicated by the numeral 24. The extension 24 of each blade is formed upon one face with a boss 25 having its outer vertical edge formed with a groove 26 and its lower edge formed with a groove 27. It will be observed that the extension 24 and its boss 25 is located at one lower corner of the respective blade, and that side of the extension and boss which is presented toward the opposite corner of the blade is of arcuate form and provided with a number of gear teeth indicated by the numeral 28, the extension and boss being formed, concentric to said teeth 28, with an opening 29. Each boss 25 is of a thickness corresponding to the thickness of the blade of which it forms a part, and in assembling the blades of each pair, the blades are arranged in overlapped

relation, as best shown in Figures 1, 3 and 4 of the drawings, with the lower end edge of each blade normally resting in engagement with the upper edge of the boss of the respective blade and with the teeth 28 of the two blades meshing. Pivot pins 30 are fitted through the openings 29 of the several blades and are secured at their ends in openings in the plate 3, and it is about these pins that the signal blades are adapted to swing, it being understood that swinging of either blade of any pair will result in corresponding swinging movement of the other blade of the pair, due to the intermeshing of the teeth 28 of the two blades.

In order that the blades may be maintained in folded position and likewise in extended position, means is provided which will now be described. The means comprises a restraining member associated with each pair of signal blades and indicated in general by the numeral 31 and this member comprises a strip 32 of metal provided with a longitudinally extending upstanding flange 33 parallel to and midway between the longitudinal edges of the strip. The strip is provided intermediate its ends with relative short overturned flanges 34 which engage the opposite edges of a leaf spring 35 which is bowed to elliptical form and its ends overlapped as at 36, and secured by the bolts 11 to the connecting portion 5 of the respective frame member 2. In this manner, the restraining members 31 are supported yieldably in position with the flange 33 of each member seating in the groove 27 in the respective blades when the signal blades are in folded position, and as the relatively adjacent ends of the grooves 26 and 27 are in communication with each other, it will be evident that when the blades are swung outwardly and downwardly to assume a horizontal position as shown in dotted lines in Figure 2 and in full lines in Figure 1, the flanges 33 will engage in the grooves 26. In the first instance, the upper edge of the flange 33 will engage squarely against the straight inner walls of the grooves 27 and the blades will be restrained against outward and downward swinging movement. However, such movement may be accomplished manually by means to be presently explained, and as one blade of a pair is swung outwardly and downwardly, the other blade will be correspondingly moved until the inner walls of the grooves 26 of these blades are squarely engaged by the upper edge of the flange 33 of the respective blade member 31, whereupon the blades will be maintained in their horizontal signal displaying position, as best shown in Figure 1 of the drawings.

Words to attract attention, such for example as "Look for" are printed, painted, or otherwise depicted upon the outer face of

each plate 3, as indicated by the numeral 37, and similar words are printed upon the faces of the blades of each pair. For example, the words "Rail" and "Out" will be 5 printed as indicated respectively by the numerals 38 and 39, upon one face of each blade of one of the pairs of blades. Thus, the word "Rail" will appear on one face of one blade of the pair and the word "Out" 10 will appear on the other face of the same blade, so that when the blades of this particular pair are in horizontal position and the signaling device is held upright, the engineer or conductor of the approaching 15 train may readily read the warning displayed and be instantly apprised of the reason for bringing his train to a standstill. Each pair of blades will, of course, be adapted to display different signals or warnings and, of course, as many pairs of blades 20 may be provided as are considered necessary to cover the various conditions which might prevail and constitute reasons for stopping an oncoming train.

25 By reference to the drawings, and particularly to Figures 1, 2 and 4 thereof, it will be observed that one blade of each pair is formed with a threaded socket 40 located in one longitudinal edge of the blade near the outer end thereof. In connection with the blades which are provided with the sockets, there is employed a finger button 41 having a threaded shank indicated by the numeral 42 adapted to be removably threaded into the socket 40 of any of the said blades.

30 In the use of the signaling device embodying the invention and assuming that one of the rails is out of place on a stretch of track, the track foreman will thread the shank of the finger piece 41 into the opening 40 in one of the pair of blades which bear the signal words "Rail out" and will then hand the device to one of the section hands who 35 will proceed along the track to a point remote from the displaced rail, withdraw the signal flag 20 from the tubular stock 13 of the signaling device for the purpose of flagging the oncoming train. After the engineer 40 has answered the flag and the engine is near enough for the engineer or conductor to read the signal, the section hand or man will hold the signaling device upright, having previously pulled upon the finger piece 41 so as to swing the two blades of the 45 said pair downwardly and outwardly to horizontal position. Therefore, the engineer or conductor will be immediately apprised of the reason why the train was 50 stopped or the warning displayed. It will be evident that inasmuch as only one of the finger pieces 41 is employed and this is associated with one of the blades of the pair 55 which is to display the desired warning signal, by the track foreman, nothing is left to

the judgment of the section hand, as he can, therefore, display only the proper signal or warning.

Having thus described the invention, what I claim is:

1. A signaling device comprising a stock, a frame carried thereby, a pair of signal blades mounted for swinging adjustment in the frame to assume a folded position and a position extending outwardly from the 75 frame in opposite directions, operative connection between the blades for effecting corresponding simultaneous movement of the blades, and yieldable means in cooperative relation with the blades to hold them in either folded or extended position and to positively move them to either extreme position after being initially moved past the center in either direction.

2. A signaling device comprising a supporting frame, a plurality of pairs of signal blades mounted therein, the blades of each pair bearing complementary parts of a warning, the pairs of blades being selectively movable to position within the bounds of 85 the frame and to position extending outwardly from the frame, and yieldable means in cooperative relation with the blades to hold them in either folded or extended position and to positively move them to either 90 extreme position after being initially moved past the center in either direction.

3. A signaling device comprising a supporting frame, a plurality of pairs of signal blades mounted therein, the blades of each 100 pair bearing complementary parts of a warning, and operative connection between the blades of each pair for effecting corresponding simultaneous movement of the blades, the pairs of blades being selectively movable 105 to position within the bounds of the frame and to extended position, and yieldable means in cooperative relation with the blades to hold them in either folded or extended position and to positively move them to 110 either extreme position after being initially moved past the center in either direction.

4. A signaling device comprising a stock, a frame carried thereby, a pair of signal blades mounted for swinging adjustment in 115 the frame to assume a folded position and a position extending outwardly from the frame in opposite directions, the blades at their relatively adjacent ends having intermeshing gear teeth for effecting corresponding 120 simultaneous movement of the blades, and a finger piece upon one of the said blades whereby it may be manually swung to effect adjustment of both blades.

5. A signaling device comprising a frame, 125 a pair of signal blades pivotally mounted in the frame and having intermeshing gear teeth, the blades being adjustable to assume a position lying within the bounds of the frame and a position extending outwardly 130

- from the frame in opposite directions, the intermeshing teeth providing for corresponding simultaneous movement of the edges of the blades, a restraining member 40 comprising a strip having a flange seating upon one of the blades whereby it may be moved.
6. A signaling device comprising a frame, a pair of signal blades pivotally mounted for swinging adjustment in the frame to assume a folded-overlapped position within the bounds of the frame and a position extending outwardly in opposite directions from the frame, and operative connection between the blades for effecting corresponding simultaneous movement of the blades.
7. A signaling device comprising a frame, a pair of signal blades mounted for swinging adjustment in the frame to assume a folded position and a position extending outwardly from the frame in opposite directions, the blades each having relatively adjacent straight edge portions, operative connection between the blades for effecting corresponding simultaneous movement of the blades, and a yieldably supported restraining member coacting with the straight edge portions of the blades for maintaining the blades in positions of adjustment.
8. A signaling device comprising a frame, a pair of signal blades pivotally mounted for swinging movement in the frame to assume a folded position within the bounds of the frame and a position extending outwardly from the frame in opposite directions, operative connection between the blades for effecting corresponding simultaneous movement of the blades, the blades
- at their pivoted ends being formed each with grooves extending along relatively adjacent edges of the blades, a restraining member 45 comprising a strip having a flange seating in the grooves and bearing against the inner walls of the grooves and constituting means for maintaining the blades in positions of adjustment, and means yieldably 50 maintaining the restraining member in engagement with the blades.
9. A signaling device comprising a stock, a frame including side frame members supported at opposite sides of the stock, a plurality of pairs of signal blades mounted within each of the side frame members for swinging adjustment to assume a folded position lying within the bounds thereof or a position extending outwardly from the frame in opposite directions, and operative connection between the blades for effecting corresponding simultaneous movement of the blades.
10. A signaling device comprising a supporting frame, a plurality of pairs of signal blades mounted therein, the blades of each pair bearing associated warning words, the pairs of blades being selectively movable to position within the bounds of the frame and to extended position, one blade of each pair having a threaded socket therein, and a finger piece having a threaded shank selectively engageable in the sockets of the said blades, the blades of each pair being connected for corresponding simultaneous movement.

In testimony whereof I affix my signature.

JOSEPH B. WELDAY. [L.S.]
